UNITED STATES PATENT OFFICE

THOMAS A. MURPHY, OF MIDDLETOWN, CONNECTICUT, ASSIGNOR OF ONE-HALF TO
BERKLEY C. STONE, OF PORTLAND, CONNECTICUT

PISTON-POSITION INDICATOR

Application filed August 29, 1930. Serial No. 478,710.

My invention relates to the class of devices employed for indicating the position of a piston in an engine cylinder, and an object of my invention, among others, is to provide an indicator for this purpose that shall be positive in its action, and that may be readily attached in place for operation.

One form of an indicator embodying my invention and in the construction and use of which the objects herein set out, as well as others, may be attained, is illustrated in the accompanying drawings, in which—

Figure 1 is a side view of my improved indicator.

Figure 2 is a view in central lengthwise section through the same.

Figure 3 shows the indicator attached to the cylinder of an engine and the position of the indicator rod at the completion of the compression stroke of the piston.

Figure 4 is a similar view but showing the position of the indicator rod immediately following the end of the compression stroke.

It is desirable in many instances to know just when the piston of an engine cylinder is at the end of its compression stroke as, for instance, when it is desired to remove the carbon by burning, as the position of the piston at this time completely protects the walls of the cylinder from injury. Again it is often desirable to note the time of ignition of the spark relative to the termination of the compression stroke of the piston so that it may be ascertained whether the ignition is taking place properly. My device, illustrated and described herein, is so arranged that the end of the compression stroke of the piston in a cylinder may be certainly and readily determined the instant it occurs.

Such device comprises a body 5 that is threaded to fit the spark plug opening for the cylinder. An indicator tube 6 is secured to the body as by means of inter-engaging screw threads, this tube having a chamber 7 therein through which an indicator rod 8 extends, the lower end of the rod having a valve 9 fitting a passage 10 extending to the end of the tube and communicating with a passage 11 extending inwardly from the end 50 of the body 5.

A cap 12 is screw threadedly engaged with the outer end of the tube 6, this cap having an opening 13 through which the stem of the rod 8 projects. The size of this opening with respect to that of the stem is exaggerated herein.

In the actual structure the stem or rod 8 will be so fitted to the opening 13 as to permit a slight vent through such opening. The clearance, however, will not be such as to prevent the stem or rod from rising by reason of pressure within the engine cylinder against the valve 9.

In the operation of the device the body 5 is applied to the spark plug opening 14 in an engine cylinder 15 and the crank shaft of the engine is then turned in the ordinary manner. As the piston 16 moves inwardly to its compression stroke in the cylinder, the pressure created thereby will be exerted against the valve 9 and the latter will be forced outwardly within the chamber 7, the stem or rod 8 being moved outwardly beyond the end of the cap 12. A steady movement being imparted to the crank shaft the stem 8 will move steadily outward until the piston 16 reaches the end of its compression stroke. The pressure within the cylinder ceasing at this instant, a sufficient vent will take place through the opening 13 to relieve the pressure in the chamber 7 and the valve 9 will at once drop to its seat thus indicating the end of the compression stroke of the piston.

In accordance with the provisions of the patent statutes I have described the principles of operation of my invention, together with the device which I now consider to represent the best embodiment thereof; but I desire to have it understood that the device shown is only illustrative, and that the invention may be carried out by other means and applied to uses other than those above set out.

I claim:

1. A piston position indicator including a member having a chamber therein and adapted to be attached to an engine cylinder for communication of said chamber with the chamber in the engine cylinder, a valve located in said chamber, a stem projecting out of said chamber, and means for providing a

vent to said chamber insufficient to prevent movement of the valve by reason of the pressure in the engine cylinder.

2. A piston position indicator including a member having a chamber therein and adapted to be attached to an engine cylinder for communication of said chamber with the chamber in the engine cylinder, a valve located in said chamber, a stem projecting out of said chamber, the size of said stem relatively to the opening therefor being such as to provide a vent insufficient, however, to prevent movement of the valve under pressure within the engine cylinder.
3. A piston position indicator including a body adapted for attachment within the spark plug opening of a cylinder, a tube projecting from said body and having a chamber therein with a passage extending from said chamber to the end of the body, a valve located in said chamber, a cap to close the end of said chamber, a stem projecting from the valve through said cap, the opening in the cap and the size of the stem being relatively such as to provide a vent insufficient, however, to prevent movement of the valve under pressure caused by movement of the piston in the cylinder to its compression stroke.
